UNITED STATES PATENT OFFICE.

ALVAH C. ROEBUCK, OF WOODSTOCK, ILLINOIS.

TYPE-WRITING MACHINE.

1,146,959.

Specification of Letters Patent. Patented July 20, 1915.

Application filed November 12, 1913. Serial No. 800,434.

To all whom it may concern:

Be it known that I, ALVAH C. ROEBUCK, a citizen of the United States, residing at Woodstock, in the county of McHenry and 5 State of Illinois, have invented certain new and useful Improvements in Type-Writing Machines, of which the following is a specification.

This invention relates to typewriters, and 10 more particularly to a platen shift key and the means for locking the shift key in upper case position.

The principal object of the invention is to provide new and improved means for maintaining the shift key in its upper case position.

The invention consists in the features of novelty in the construction, combination and arrangement of the several parts generally 20 shown and described in the specification, but more particularly pointed out in the appended claims.

In the drawings, Figure 1 is a view in elevation illustrating the invention, parts of 25 the typewriting machine being omitted for clearness; Fig. 2 is a detail view with the locking latch in engaging position; and Fig. 3 is a sectional detail on the line 3—3 of Fig. 1.

30 Referring more particularly to the drawings the numeral 3 designates generally a typewriter frame in which a carriage 4 is mounted in the well known manner upon ways 5, and a rotary member 6 is supported 35 by the carriage and is adapted to engage a rail 7 carried by a pivotally mounted member 8 having an engaging surface 9, the movement of which member 8 causes the movement of the platen 10 to the upper and 40 lower case positions in the well known manner. Abutting the engaging surface 9 of the pivotally mounted member 8 is one extremity 11 of a shift key 12, which is pivotally mounted adjacent the rear of the machine 45 in a support 13, which support also carries a spring 14 with an adjusting screw 15, for pressing the shift key normally upward. The forward end of the shift key 12 is provided with a finger button base 16 by means 50 of which it may be depressed against the spring 14 to raise the platen 10 into upper case position. A slotted guide 17 is disposed at the front of the machine with a detent 18 projecting therefrom to engage a lateral 55 projection 19 on the key 12 to limit the

downward movement thereof. This shift key is formed with a depending projection 20 having a curved face formed with a radius from the axis of the key lever or with a notch 22 at a distance from the extremity 60 of the projection and at right angles to the vertical forward face. Pivotally connected to the key 12 adjacent the forward end is a lock lever 23 having a finger button 24 at one end and the other end having a portion 25, 65 one edge of which forms a continuation of the vertical surface 21 when the lever is in normal position, and with a wedging surface 26 which extends from the point of the notch 22 downwardly and rearwardly therefrom and at an angle to the vertical face. This lever 23 is also provided with a slot 27 through which a pin 28 projecting from the lever 12 extends to limit the rotative movement of the lock lever. The lever is also 70 formed with an arm 29, and extending between the arm 29 and the pin 28 is a spring 30 which tends to draw the lock lever in such a position that the portion 25 covers the notch 22 and forms a continuation of the 75 vertical surface 21.

A latch 31 is pivotally mounted on a pin 35 secured to the frame of the machine and comprises an engaging arm 32 having a lateral edged lip 34 adapted to bear against the 80 vertical surface 21 and to engage in the notch 22 when the key is depressed and when the notch is uncovered by the rotation of the lever 23, and an arm 33 which forms a weight for pressing the lip 34 yieldingly 85 against the said vertical surface and tending to cause the engagement of the latch with the notch. Upon releasing the finger pressure on button 24, the upward pressure of spring 14 against the key 12 will exert 90 sufficient upward pressure on lip 34 to prevent the wedging surface 26 from moving the lip 34 out of engagement with the notch 22 of the shift key.

In operation when it is desired only to 100 shift the platen for a single character or to hold the shift key down manually, the key is depressed by pressure on the button 16, but when it is desired to lock the key in upper case position the shift key 12 is rotated by pressure on the button 24 of the lever 23 which rotates the lever and uncovers the notch 22 and permits the lip 34 of the latch 31 to engage in the notch. To return the key to normal or lower case 110

position all that is necessary is a slight pressure on the forward end of the key 12 by pressing the button 16 sufficiently to relieve the upward pressure of the spring 14 which holds the lateral lip 34 in engagement with notch 22, whereupon the wedging surface 26 of the lever 23, through the action of its spring 30 will wedge the lip 34 of the latch out of engagement with the 10 notch 22.

What I claim is:

1. In a typewriter, a shift key having a depending projection with a notch in the face thereof, a lock lever pivoted to the key 15 with a depending portion normally to cover the notch, and means to engage the notch when the shift key is depressed and the lock lever moved to uncover the notch.

2. In a typewriter, a shift key having a 20 depending portion with a straight edge on one side and a notch at the top of the straight edge at a distance from the extremity of the projection, a lock lever pivotally connected to the key and having an arm 25 adapted to form a continuation of the straight surface of the projection on the shift key, and a latch adapted to engage in the said notch when the shift key is depressed by moving the lock lever to uncover 30 the notch.

3. In a typewriter, a pivotally mounted shift key having a projection with a vertical face with a notch at the top of the face at a 35 distance from the end of the projection, a pivotally mounted latch adapted to bear yieldingly on the said vertical surface and to engage in the notch when the shift key is depressed, and a lock lever pivotally mounted on the shift key having a portion 40 normally forming a continuation of said vertical surface and preventing the engagement of the latch with the notch and movable about its pivot to permit the latch to engage the notch when the key is depressed.

4. In a typewriter, a pivotally mounted shift key having a projection with a vertical face in which there is a notch at a distance from the end of the projection, a pivotally mounted latch adapted to bear yieldingly 50 on the said vertical surface and to engage in the notch when the shift key is depressed, a lock lever having a projection to form a continuation of the said vertical surface and normally to prevent the latch from engaging 55 in the notch of the shift key, a pin on the shift key, the said lock lever being formed with a slot in which the pin projects to limit the pivotal movement of the lever, and a spring connecting the lock lever with the 60 pin to hold the lever yieldingly in position to prevent the engagement of said latch.

5. In a typewriter, a frame, a shiftable platen, a pivotally mounted key for shifting the platen, a stop on the key to engage the 65 frame to limit the movement of the key, the

said key being formed with a depending projection having a substantially vertical face with a notch at right angles thereto and at a distance from the end of the projection, a lock lever having a button base at one end 70 and a projection at the other end adapted to form a continuation of the said vertical face and with a beveled extremity pivotally connected to the side of the shift key, means to limit the movement of the lock lever with 75 respect to the shift key, a spring connecting the lock lever and the key to hold the lever in position to cover the notch, and a pivotally mounted latch comprising a lever with one arm formed to engage the notch of the 80 shift key when the lock lever is rotated against the spring and the other arm forming a weighted projection to press the engaging arm yieldingly in contact with the vertical face in position to engage the notch. 85

6. In a typewriter, a shift key formed with a depending projection having a substantially vertical front face with a notch at right angles thereto at a distance from the end of the projection, a lock lever pivotally connected to the shift key having an arm forming a continuation of the vertical face from the angular point of the notch and with a wedging surface extending rearwardly from the point of the notch, means in 90 connection with the lever and shift key to hold the lever yieldingly in position to form a continuation of said vertical surface, and a weighted pivoted latch bearing yieldingly against the vertical surface and adapted to 95 engage the notch when the lock lever is rotated with respect to the key, the beveled extremity of the lock lever being adapted to press the latch out of engagement with the notch by the pressure of the said resilient 100 means.

7. In a typewriter, a shift key having a depending projection with a notch in the edge thereof, a lock lever pivoted to the key 110 with a portion to cover and uncover the notch at the side thereof, and a pivotally mounted latch with an arm having a lateral projection adapted to engage in the notch and the other arm acting as a weight to 115 press the projection yieldingly into engaging position.

8. In a typewriter, a shift key having a depending notched projection, a lock lever pivoted to the key having a wedging surface at the end, a pivotally mounted weighted 120 latch with a lateral projection having an inclined surface, a spring tending to press the shift key to hold the projection of the latch in the notch, and a spring in connection with the lock lever to press the wedging surface against the inclined surface of the lateral projection when the latter is in the notch. 125

9. In a typewriter, a shift key having a depending engageable projection, a pivotally mounted latch with one arm to engage the 130

lever and with another arm weighted to hold the lever in such engagement, and a lock lever pivoted to the shift key adapted to prevent the engagement of the latch when the key alone is depressed and to permit such engagement when the lock lever is moved relatively to the key.

5 In testimony whereof I have signed my

name to this specification, in the presence of two subscribing witnesses, on this 7th day of 10 November A. D. 1913.

ALVAH C. ROEBUCK.
